UNITED STATES PATENT OFFICE.

WILLIAM S. BALDWIN, OF WORCESTER, MASSACHUSETTS, ASSIGNOR TO MERGEN-
THALER LINOTYPE COMPANY, A CORPORATION OF NEW YORK.

TYPOGRAPHICAL MACHINE.

1,106,613.

Specification of Letters Patent. Patented Aug. 11, 1914.

Application filed January 24, 1913. Serial No. 743,913.

To all whom it may concern:

Be it known that I, WILLIAM S. BALDWIN, citizen of the United States, residing at Worcester, in the county of Worcester and 5 State of Massachusetts, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices 15 are released from a magazine in the order in which their characters are to appear in print and then assembled in line, the composed line transferred to the face of a mold, the mold filled with molten metal to form a 20 slug or linotype against the matrices which produce the type characters thereon, and the matrices thereafter returned through a distributing mechanism to the magazine from which they started.

25 More particularly, it relates to the means for injecting the molten metal into the mold, and it is the aim of my invention to provide devices whereby these injecting means may be arrested at will, and this preferably 30 by a manually-operable handle or lever within convenient reach of the operator.

Linotype machines have been provided in the past with automatic mechanism whereby the pump is prevented from acting in 35 various contingencies, as for instance if the line of matrices be not assembled in close order and clamped tightly together between the confining jaws. Such mechanism is presented in Letters Patent of the United 40 States to G. A. Bates, No. 659,865. In this and other similar constructions, the metal-injecting mechanism is normally locked against actuation, and is unlocked only in the event that the line be properly compacted 45 between the jaws.

It is one of the principal purposes of my improvements to permit the locking of the metal-injecting mechanism, even after it has been unlocked in the manner indicated.

50 This is desirable in many instances, as for example when the operator wishes to prevent the casting of "pi" lines, or even to prevent "squirts" in the event that the automatic stop is not properly operating.

55 In the accompanying drawings, I have

shown my invention in preferred form and by way of example, and as applied to a linotype machine, but obviously many modifications and variations may be made therein, and in its mode of application, which will 60 still be comprised within its spirit. Thus, it may be applied to any form of typographical machine comprising casting mechanism, such as typecasters, etc., etc.

Generally speaking, I desire it to be understood that I do not limit myself to any specific form or embodiment, except in so far as such limitations are specified in the claims.

In the accompanying drawings: Figure 1 70 is a plan view, showing the pot, mold disk, pump-stop connections, etc., etc., with my invention applied thereto; Fig. 2 is a front view of a portion of the machine in the vicinity of the intermediate channel; and 75 Fig. 3 is a rear view of the pot and the pump-stop devices.

The matrices are delivered to the assembler A, which is then elevated and the line transferred therefrom through the intermediate channel B to the first elevator C, by which in turn it is presented to a mold, carried by the mold disk D, and wherein the slug is cast, the molten metal being supplied thereto from a pot E. The parts so far 80 described, and their operation, are or may be substantially the same as those disclosed in the said Mergenthaler patent.

The metal-injecting means comprise the pump-plunger F connected to the actuating 90 lever G, the plunger and lever being held against operation by locking devices P, unless the line be properly compacted between the jaws, all as disclosed in the said Bates patent. As therein described, the locking 95 devices P normally hold the lever G and plunger F against movement, and permit them to descend only when a proper matrix line acts to move the jaw. It is the aim of my invention to add devices whereby the parts may be locked at will, and preferably 100 by a manual act of the operator, for the purposes previously mentioned.

In my preferred form, these stop devices 105 comprise a stop arm H, pivotally connected to the frame of the pot E, so as to swing therewith, and also capable of a movement relatively thereto to engage its upper end under the projecting block G' carried by the lever G, in such manner as to prevent its 110

downward movement and the consequent ejection of the metal. A spring H' normally holds the arm H out of the path of the block G', and serves to return the arm to its outward position after it has been operated. For the purpose of shifting the arm H, any suitable connections may be employed, in the form shown, these comprising the cord J connected thereto and passing over a pulley 10 K to the operating handle L, located at the front of the machine and in convenient proximity to the operator.

In Fig. 1, the pot E is shown in its retracted position, and at this time the stop arm H is similarly in inoperative relation to the block G', as indicated by full lines therein. When the pot moves forward to co-operate with the mold, the arm H moves with it, until it assumes the dotted-line position, when it is in readiness to be shifted under the block G' by the manipulation of the devices previously described.

As before stated, I have shown my invention only in preferred form and by way of example, and obviously many changes and alterations therein, and in its mode of application will suggest themselves to those skilled in the art without departure from its scope.

Having thus described my invention, its construction and mode of operation, what I claim and desire to secure by Letters Patent of the United States, is as follows:

1. In a typographical machine comprising

ing casting mechanism, the combination of 35 metal injecting means, stop devices controlled automatically for arresting their actuation, and separate and independent stop devices under the exclusive control of the operator for arresting the actuation of said 40 means at will.

2. In a typographical machine comprising casting mechanism, the combination of the pump lever; an automatic stop therefor, a further adjustable stop for the pump lever 45 under the exclusive control of the operator, and manually operable connections from said stop and extending to the front of the machine in proximity to the key-board; whereby the action of the pump lever may 50 be instantly prevented at the will of the operator while seated at the keyboard.

3. In a typographical machine comprising casting mechanism, the combination of the pump lever G, the automatic stop device P 55 therefor, the pivoted stop-arm H under the exclusive control of the operator, the handle L arranged in proximity to the key-board, and connections therefrom to the arm H; whereby the operation of the pump lever G 60 may be instantly prevented at the will of the operator while seated at the keyboard.

In testimony whereof I affix my signature in presence of two witnesses.

WILLIAM S. BALDWIN.
